UNITED STATES PATENT OFFICE

CARL E. KENDRICK AND BERT W. MOORE, OF LITHIA, FLORIDA; SAID MOORE ASSIGNOR
TO SAID KENDRICK

COMPRESSION BRAKE FOR HOISTING DRUMS

Application filed July 13, 1929. Serial No. 378,098.

The present invention relates generally to a hoisting drum and has for its prime object to provide a compression brake operatively associated therewith.

Another very important object of the invention resides in the combination of a hoisting drum with a piston reciprocably mounted in a cylinder and operatively connected with the hoisting drum, and a valve mechanism associated with the cylinder to control the intake and exhaust of air therefrom occasioned by the reciprocation of the piston so that said means may be shut off causing a braking action on the pistons which is effective on the drum to said connecting means.

A still further very important object of the invention resides in the provision of a mechanism of this nature which is simple in its construction, inexpensive to manufacture, easy to manipulate, compact and convenient, strong and durable, thoroughly efficient and reliable in use and operation, and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawings:

Figure 1 is a side elevation of an apparatus embodying the features of our invention.

Figure 2 is a top plan view thereof, showing the cylinder in section, and

Figure 3 is an enlarged detail section taken substantially on the line 3—3 of Figure 1.

Referring to the drawings in detail, it will be seen that the numeral 5 denotes a base, with the standard 6 arising therefrom, on which is rotatably mounted a drum 7, having driving means 8 associated at one end thereof and at the other end being formed with a gear 9. The gear 9 meshes with the gear 10 on the shaft 11 journaled in bearings at the upper end of the standard 12 rising from the base 5. A wheel or disc 14 is fixed to the shaft 11 at the opposite end to the gear 10 and has an off center pin 15 projecting therefrom with which is engaged a connect-

ing rod 16. The numeral 17 denotes the piston cylinder, mounted in supports 18 rising from the base and held in place by straps 19 or in any other suitable manner. Heads 20 and 21 are provided at the ends of the cylinder. The head 21 is provided with the stuffing box 22 at the center thereof through which is slidably a piston 24, reciprocably mounted in the cylinder 17. Pressure actuated safety valves 26 are mounted in the heads 20 and 21. Air intake and outlet pipes 27 lead from the ends of the cylinder and have valves 28 provided with valve operating cranks 29 connected by a control rod 30, so that the valves may be opened and closed simultaneously.

From the above detailed description it will be seen that when the valves 28 are opened, the piston 24 reciprocates back and forth freely, offering very little resistance to the turning of the drum 7, either by the mechanism 8 or by the load on the cable 7' when wound thereon, but when it is desired to brake the drum 7, it is only necessary to close the valve 28, and thus a compression brake is formed as the piston tends to compress the air in the ends of the cylinder and this braking action is transmitted to the drum through the rods 23 and 16, wheel 14, shaft 11 and gearing 9. When compression at either end of the cylinder approaches a dangerous limit, the valve 26 automatically opens to permit escape of air and consequent reduction of pressure.

It is thought that the construction, operation, utility and advantages of this invention will now be quite apparent to those skilled in this art without a more detailed description thereof.

The present embodiment of the invention has been disclosed in considerable detail merely for the purpose of exemplification, since in actual practice it attains the features of advantage enumerated as desirable in the statement of the invention and the above description. It will be apparent that changes in the details of construction and in the combination and arrangement of parts may be resorted to, without departing from the spirit or scope of the invention as hereinafter

claimed or sacrificing any of its advantages.

What we claim as new is:

A compression brake comprising a cylinder, a piston in said cylinder, adapted to be connected to the member to be braked, air intake and outlet pipes communicating with the cylinder adjacent opposite limits of the travel of said piston, a normally open valve in each pipe, an operating rod connecting each valve for simultaneously closing and opening same to regulate the escape and entrance of air from and into said cylinder, and a pressure actuated valve at each end of the cylinder operable to open the cylinder to the atmosphere when the pressure therein exceeds a predetermined amount.

In testimony whereof we affix our signatures.

CARL E. KENDRICK.
BERT W. MOORE.
